US0D1078481S

(12) **United States Design Patent** (10) **Patent No.:** **US D1,078,481 S**
(45) **Date of Patent:** **** Jun. 10, 2025**

(54) **COSMETIC JAR**

(71) Applicant: **The Procter & Gamble Company**,
Cincinnati, OH (US)

(72) Inventors: **Andrew Dapore**, Cincinnati, OH (US);
Graham Clive Hutton, New York, NY
(US)

(73) Assignee: **The Procter & Gamble Company**,
Cincinnati, OH (US)

(**) Term: **15 Years**

(21) Appl. No.: **29/915,060**

(22) Filed: **Oct. 25, 2023**

Related U.S. Application Data

(62) Division of application No. 29/812,028, filed on Oct. 19, 2021, now Pat. No. Des. 1,014,269.

(51) **LOC (15) Cl.** **09-01**

(52) **U.S. Cl.**

USPC **D9/558**; D9/529

(57) **CLAIM**

The ornamental design for a cosmetic jar as shown and described.

DESCRIPTION

FIG. 1 is a perspective view of a cosmetic jar, showing our new design;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines shown in the drawings depict portions of the cosmetic jar that form no part of the claimed design.
